UNITED STATES PATENT OFFICE.

ARTHUR J. SAALFIELD, OF BROOKLYN, NEW YORK.

DESIGN FOR A BOOK-COVER.

SPECIFICATION forming part of Design No. 25,822, dated July 21, 1896.

Application filed May 28, 1896. Serial No. 593,519. Term of patent 3½ years.

To all whom it may concern:

Be it known that I, ARTHUR J. SAALFIELD, a citizen of the United States, residing at Brooklyn, in the county of Kings and State 5 of New York, have invented and produced a new and original Design for a Book-Cover, of which the following is a specification.

My design is illustrated in the accompanying drawing, which shows a face view of a 10 book-cover ornamented according to my invention.

In the drawing the letters A B designate 15 two leaves which emanate from two stalks C D and cross each other. From these stalks

ends of said stalks are flowers G H. The bottom ends of the stalks C D are connected by a horizontal stalk I, from which emanate two curved stalks J K, which bear flowers L M.

What I claim as new, and desire to secure 20 by Letters Patent, is—

The design for a book-cover herein shown and described.

In testimony whereof I have hereunto set my hand in the presence of two subscribing 25 witnesses.

ARTHUR J. SAALFIELD.
